TOOL FOR REMOVING RAILWAY TIES

Louis Stotka, Baldwin, Wis., assignor of two-thirds to Anton M. Hendrickson and Ralph R. Strother, both of St. Paul, Minn.

Application May 13, 1942, Serial No. 442,775

11 Claims. (Cl. 254—44)

This invention relates to a device for removing railway ties that have become worn out, badly decayed or damaged, the device being used when it is desired to replace individual old ties by new ones and without removing the rails.

It is an object of my invention to provide a novel, simple and inexpensive tool adapted to facilitate the rapid removal of railway ties from beneath the rails.

Other objects are to provide a tool of this character which is strong, easy to operate and adapted for use with rails of different sizes.

The invention will be best understood by reference to the accompanying drawings in which:

Figure 1 is a side elevation showing a simple form of my device and illustrating a method of using it for the removal of a tie from beneath a pair of rails, shown in cross section.

Fig. 2 is a plan view of the lever shown in Fig. 1 with the tie-engaging member disposed at right angles to the lever;

Fig. 3 is a side elevation showing the parts in the same relative positions as in Fig. 2;

Fig. 4 is an end elevation as viewed from the right of Fig. 3;

Fig. 5 and 6 are plan and side views respectively of the fulcrum end of the simpler form of lever and showing an attachment for adapting the tool to fit the heavier or larger rails;

Fig. 7 is a side elevation showing a preferred form of my invention in operative relation to a rail and tie and with a portion of the lever handle broken away;

Fig. 8 is a plan view of the assembly shown in Fig. 7;

Fig. 9 is a side elevation of the tool as viewed from the right of Fig. 7 and with the rail removed, and

Fig. 10 is a fragmentary, horizontal section taken on the line 10—10 of Fig. 7.

In the simpler form of my device I provide a lever having a long handle 7 and a pair of fulcrum members 8 rigidly secured to an end portion of the handle 7 and formed with cylindrical bearings 9 for engagement with the web and flange of a rail. The fulcrum members 8 are rectangular in cross section and are preferably welded to opposite faces of a rectangular end portion 7a of the handle 7. Each of the members 8 has a laterally projecting end formed with an end surface 10 to fit beneath and engage the head or bead of a rail. The cylindrical fulcrum surfaces 9 engage the rail at points spaced a substantial distance apart and thus facilitate

movement of the handle in a plane which is perpendicular to the rail.

A tie-engaging member is pivotally joined to the lever and comprises a pair of side bars 11 and a central bar 12, all rigidly maintained in parallel relation to each other, and each having a pointed end 13 to engage a tie. The opposite ends of the bars 11 are formed to receive a bolt 14 which pivotally connects the tie-engaging member to the handle 7 and fulcrum members 8. The bars 11 and 12 are held in spaced, parallel relation to each other by tubular spacers 15 mounted on bolts 16 which rigidly connect the bars 11 and 12.

To adapt the fulcrum members 8 to fit rails of various heights, I provide a pair of extension blocks 17 which are formed to be detachably mounted on the ends of the members 8, as shown in Figs. 5 and 6. Each of the blocks 17 has a pair of ears 18 formed thereon to fit opposite faces of a fulcrum member 8 and these ears 18 are pierced to receive bolts 19 for fastening the blocks 17 in place, a perforation 20 (Fig. 3) being provided near the end of each member 8 for a bolt 19.

My device may be used as indicated in Fig. 1 to remove a tie 21 from beneath a pair of rails 22. The ballast or fill 23 in which the ties are imbedded is cleared away from an end of the tie 21, as indicated at 24, preparatory to removing the tie and in further preparation for removing the tie 21 the rail spikes are withdrawn from that tie and in most cases the rails are jacked up sufficiently to relieve the weight on the tie and to clear any tie cuts which may have been formed by the rails. After such preparation my improved tool is applied with the handle 7 approximately in the position shown in full lines in Fig. 1, the fulcrum bearings 9 being spaced in engagement with the inner flange and web of one rail and the end surface 10 fitting beneath the head of the rail. The operator now presses down on the free ends of the tie-engaging bars 11 and 12 to cause the pointed ends 13 to bite into the tie while the handle 7 is oscillated from the full line position toward the dotted line position shown in Fig. 1 and back to starting position repeatedly. One foot of the operator is preferably used to press down on the bars 11 and 12.

At each swing to the right the tie is forced a short distance to the right and the step by step movement is continued until the tie is beyond the reach of the bars 11 and 12. At this point the tool may be removed to the outer side of the rail to the right, as seen in Fig. 1, and op-

erated in a similar manner until the tie is free of both rails.

During the operation of the device, and particularly at the start of each power stroke, the ends 10 of the fulcrum members 8 engage the underside of the head of the rail to prevent the fulcrum from being forced up by the resistance directed upward along the bars 11 and 12. It will be evident that the members 8 and tie-engaging members 11 act as toggle members and when they are moved toward their aligned position exert great force to move the ties longitudinally. Where rails of the heavier or larger sizes are encountered, the blocks 17 are attached to the ends of the fulcrum members 8, as shown in Figs. 5 and 6. These blocks operate like the ends 10 of the fulcrum members 8 to engage beneath the rail head and prevent the upward shifting or release of the fulcrum from the rail when the device is in use.

In the preferred form of my device illustrated in Figs. 7 to 10 inclusive a manually operable lever 25 is pivotally supported on a fulcrum member 26 which is formed to fit the side of the rail 22 between the flange and head. A pair of abutment screws 27 are threaded in the member 26 to engage the bottom surface of the rail head at points spaced along the rail. By suitable adjustment of these screws the fulcrum member 26 may be caused to fit and be confined beneath rail heads of various heights. It will be understood that for the larger rails these screws may be turned to project further from the member 26 and for the smaller rails the screws are turned into said members. The lower end of the lever 25 extends into an opening 28 (Fig. 10) formed centrally in the member 26 and is pivotally connected to the latter by a bolt 29.

Tie engaging bars 30 and 31 are pivotally connected to the lever 25 by a pin 32 which is spaced along the lever 25 from the bolt 29. The free ends of the bars 30 and 31 are formed with teeth 33 adapted to bite into the tie 21 and these bars are rigidly connected together by a plate 34 near their free ends and by a plate 35 near their pivotally supported ends. Pivoted on the bolt 29 and projecting therefrom in substantially parallel relation to the tie 21 is a pair of rods 36 having free ends 37 extending obliquely downward toward the tie and formed with sharpened extremities adapted to penetrate the tie sufficiently to retain the member 26 in engagement with the rail while the teeth 33 are withdrawn from the tie during the upward stroke of the lever 25. A cross rod 38 is welded to the rods 36 near their free ends to rigidly connect them.

A suitable stop is provided to limit the arc of movement of the lever 25 relative to the fulcrum member 26 and prevent the fulcrum member from being forced out of contact with the rail by engagement of the lever 25 with the rail head. This stop comprises a short cross bar 39 which is welded to the lever 25 and projects at the sides thereof to engage the inner face of the member 26 near its upper edge. Downward oscillating movement of the bars 30 and 31 relative to the lever 25 is also limited by providing a stop shoulder 40 on the lever disposed to be engaged by the plate 35.

In operation of the preferred form of my invention, assuming that the spikes connecting the rail 22 to the tie 21 have been withdrawn, the fulcrum head 26 is placed in engagement with the flange, web and head of the rail 22 as shown, the lever 25 is elevated to its vertical position

and then the operator impresses the teeth 33 into the tie by stepping on the plate 34, as indicated in full lines in Fig. 7. Now one or more workmen move the upper end of the lever 25 to the left and downward as seen in Fig. 7 thus forcing the tie 21 to the left relative to the rails while the pointed ends 37 of the rods 36 slide over the top surface of the tie. Upon completing the downward stroke, the operator steps on the rod 38 to impress the ends 37 of the rods 36 into the tie and then the lever 25 is raised and moved to the substantially vertical starting position. During this upward stroke the teeth 33 are withdrawn from the tie and the rods 36 retain the fulcrum member 26 in engagement with the rail. The oscillating movement of the lever and operation of the tie-engaging members 30, 31 and 36 is repeated until the tie has been removed longitudinally from beneath the rails, as more fully described with reference to the form of the invention shown in Figs. 1 to 4 inclusive.

It will be understood that the rods 36 facilitate the operation by preventing the fulcrum member 26 from being moved away from the rail under the force exerted when the teeth 33 are withdrawn from the tie during the upward stroke of the lever. The operation is further facilitated by providing the elongated fulcrum member and duplicate tie-engaging members 30 and 36 which form a wide and stable supporting base for the tool. Similarly, in the form of my device shown in Figs. 1 to 6 inclusive, by providing the spaced duplicate fulcrum members 8 and series of spaced tie-engaging bars 11 and 12, I facilitate oscillating movement of the lever in the proper plane which is perpendicular to the rail or substantially vertical and thus guard against bending of the tie-engaging members out of alignment with the lever when force is applied to the handle. The plurality of tie-engaging bars also distribute the force applied to the tie. Extensive use of my improved tie removing devices has demonstrated that they reduce labor and equipment costs as compared with the use of other known machines and tools for removing ties.

Having described my invention, what I claim as new and desire to protect by Letters Patent is:

- 50 1. A tool for removing railway ties comprising, a lever having a fulcrum member formed to engage a rail and affording a pivotal support for the normally lower end of said lever, a tie-engaging member pivotally connected to said lever at a point spaced from the fulcrum member, means projecting from the free end of said tie-engaging member for pivotally engaging a tie, said lever being operable to and from a position wherein its fulcrum is in substantial alignment with its pivot connection with said tie-engaging member and with said projecting means to force a tie longitudinally from beneath the rail.
- 55 2. A tool for removing railway ties comprising, a lever having a fulcrum formed to engage the flange, web and head of a rail, a thrust member pivotally connected to said lever at a point spaced from the fulcrum, said member extending obliquely to the tie to be removed, means projecting from the free end of said thrust member for making a hinge-like connection with the tie at successive points longitudinally thereof while said lever is oscillated to force the tie longitudinally from beneath said rail and means for adapting said fulcrum to engage rail flanges and heads variously spaced.

3. A tool for removing railway ties comprising, a lever having an elongated handle and a fulcrum formed to engage a side of a rail and spaced tie-engaging bars pivotally connected to said lever, extending therefrom along and toward a tie and having free ends adapted to hingedly engage the top of a tie at successive points spaced from said rail while said handle is oscillated in a substantially vertical plane to remove the tie, step by step, from beneath the rail.

4. A tool for removing railway ties comprising, a lever, a fulcrum member for said lever adapted to engage a rail, a tie-engaging member pivotally connected to said lever at a point spaced from the rail and above the fulcrum member, said tie-engaging member having a free end adapted to make an oscillatory connection with the tie at successive points spaced from said rail while said handle is oscillated in a substantially vertical plane to remove a tie, step by step, from beneath a rail and means for retaining said fulcrum member in engagement with the rail during the oscillating movement of the lever.

5. A tool for removing railway ties comprising, a lever having an elongated handle, a fulcrum member for said lever formed to engage a rail, said lever being pivotally supported on said member, and thrust means pivotally connected to said lever at a point removed upward from said fulcrum member, said thrust means extending obliquely downward and having a free end member adapted to make an oscillatory connection with the top of a tie at successive points spaced from said rail while said lever is oscillated to remove the tie, step by step, from beneath the rail.

6. A tool for removing railway ties comprising, a lever, a fulcrum member formed to fit in engagement with the flange, web and head of a rail, means pivotally connecting an end of the lever to said fulcrum member and thrust means pivotally connected to said lever extending obliquely downward therefrom longitudinally of the tie and formed to make a hinge-like connection with a tie at successive points spaced from said rail while said lever is oscillated to remove the tie, step by step, from beneath the rail.

7. A tool for removing railway ties comprising, a lever, a fulcrum member for said lever formed to engage a rail, tie-engaging means pivotally connected to said lever at a point removed from the fulcrum member above the same and formed to bite into the top of a tie at points spaced from said rail and means for retaining the fulcrum member in contact with the rail when said lever

is oscillated to remove a tie from beneath the rail.

8. A tool for removing railway ties comprising, a lever, a fulcrum member for said lever formed to engage a rail, a tie-engaging member pivotally connected to said lever at a point removed from the fulcrum member and formed to bite into the top of a tie at points spaced from said rail and a second tie-engaging member pivotally connected to said fulcrum member and lever for retaining the fulcrum member in contact with the rail when said lever is oscillated to remove a tie from beneath the rail.

9. A tool for removing railway ties comprising, a lever, a fulcrum member adapted to fit in engagement with the flange, web and head of a rail, means pivotally connecting an end of the lever to said fulcrum member, a pair of spaced tie-engaging bars pivotally connected to said lever at a point removed from the fulcrum member and each having an end formed to bite into the top of a tie at successive points spaced from said rail while said lever is oscillated to remove the tie, step by step, from beneath the rail and a pair of rods connected to the fulcrum member and extending along said tie with ends adapted to penetrate the tie to retain the fulcrum member in engagement with the rail during the oscillating movement of the lever.

10. A tool for removing railway ties comprising, a lever, a fulcrum member for engagement with a rail, extensible and retractile means for adapting said member to fit between the flange and head of rails of various sizes, means pivotally connecting an end of the lever to said fulcrum member, and tie-engaging means pivotally connected to said lever at a point removed from the fulcrum member and formed to bite into a tie at successive points spaced from said rail while said lever is oscillated to remove the tie, step by step, from beneath the rail.

11. A tool for removing railway ties comprising, a lever having a fulcrum member formed to engage a rail, said member affording an oscillatory support for the normally lower end of said lever, a rigid thrust member pivotally connected to said lever at a point spaced from the fulcrum member and being adapted to extend obliquely toward a tie beneath the rail, means projecting from the free end of said thrust member for making an oscillatory connection with the tie, the lever being operable to and from a position wherein its fulcrum is in substantial alignment with its pivot connection with said thrust member and with said projecting means to force a tie longitudinally, step by step, from beneath the rail.

LOUIS STOTKA.
